Walter H. Murphy, ^{ATTORNEY}

UNITED STATES PATENT OFFICE

DANIEL W. LENAHAN, OF NEW YORK, N. Y.

HEATING UNIT

Application filed May 11, 1928. Serial No. 277,086.

My invention relates generally to a heating unit and while not limited in its application, is particularly adapted for store, shop, garage, chicken house, greenhouse, or other single room use, to replace a stove, gas heater or the like.

The invention has for its object first, to provide a unit having ample heating capacity; second one which will operate efficiently at comparatively low cost, in fuel consumption; and, third, an arrangement such as will occupy a minimum amount of floor space.

In addition to the foregoing, the invention is designed to be constructed largely, if not entirely, from standard stock parts, requiring no special castings or fittings and is adapted to be as readily, easily and quickly installed as an ordinary coal stove.

A construction suitable for carrying my invention into effect is illustrated in the accompanying drawings, but I do not wish to be understood as limiting myself to either the form or details shown, as various changes may be made therein without departing from the spirit and scope of the invention.

In the drawings—

Fig. 1 is a view in side elevation, with portions broken away to more clearly show the construction;

Fig. 2 is a top plan view and partial section on the line 2—2, of Fig. 1; and

Fig. 3 illustrates a slightly modified construction.

Referring to the drawings, I have shown as the preferred embodiment of the invention, a wall type of heater, which employs a flat coil 1 of a suitable number of turns, depending upon the size of the room in which the heater is used.

The coil is provided at 2 with a valved water inlet, and at 3, 3, etc., with requisite air vents or valves.

The coil may be bracketed or strapped to the side or end wall of a room, as indicated at 4, 4, or otherwise secured in position, and has its ends connected by a chambered member here shown in the form of a pipe 5, provided with a steam gage 6, to indicate the pressure generated in the coil. As shown, the pipe or member 5 is of greater diameter

and considerably heavier than the piping of the coil.

In connecting the ends, the coil is made continuous, providing an unobstructed passage through the same for steam and a condensation return to the lower part thereof.

Leading outward from the lower end of the pipe 5 and forming, in effect, a continuation or extension of the lower end of the coil, there is an approximately J-shaped connection 7, which terminates in a dead end—that is to say, a closed end 8.

I have found that by applying and limiting the application of heat to this dead-end connection and the pipe 5, the required steam pressure can be rapidly generated and maintained in the coil, at a considerable saving in the consumption of fuel, over what would be used in heating the coil throughout its entire length.

As economy of maintenance, without appreciable lowering of efficiency, is the most important item to the user of any heating system, I am enabled to effect such a saving in cost by heating the above mentioned comparatively small portion of the coil.

As shown, a gas or other suitable flame, indicated by the burner 9, is provided to play directly on the J-shaped connection 7 of the coil, and, in order to avoid unnecessary waste of heat, the burner and J-shaped coil connection together with a portion of the pipe 5, are enclosed in a casing or fire box 10.

The fire-box 10 is constructed of sheet iron or steel, lined with asbestos, and is provided with a suitable door 11, giving access to the interior, and also with a flue 12, for the escape of burnt gases to a chimney or other outlet. A supply of fresh air for the burner, is admitted to the fire box through a series of small openings 13. Extending transversely of the fire box, there is a vertically disposed baffle plate 14, which prevents the immediate escape of the hot gases to the flue and tends to direct them downwardly for further heating the dead-end connection.

The modification shown in Fig. 3 differs in one respect only from the form shown in Figs. 1 and 2. The difference referred to consists in having the flue 12, from the fire-box, so

arranged as to surround or include the entire length of the pipe 5. Such an arrangement, as will be apparent, utilizes the escaping products of combustion, while in a highly heated state, to supplement the action of the burner flame in generating steam for the heating coil.

In the operation of the unit, water, to a suitable depth, is admitted to the lower part 10 of the coil through the valved inlet 2. The valve 15, controlling the supply of gas or other fuel to the burner, is opened and a light applied through the fire-box door.

The flame playing directly on the dead-end connection and indirectly heating the pipe 5 and any other portions of the coil included within the fire box, raises the temperature of the contained water to the point required for rapid conversion into steam, which, under the 20 pressure developed, passes by way of the pipe 5 to the coil, as indicated by the arrows in Fig. 1. Steam bubbles entering the highly heated pipe 5, are instantly converted into dry steam, a continuous supply of which is 25 delivered to the coil.

It will also be apparent that two or more coils and connections, as above described, may be employed in connection with a single burner and fire box and such coils arranged 30 side by side, end to end or otherwise, as desired.

As the main advantages of the invention will be evident from the foregoing description, they will not be further described.

Having thus described my invention, what I claim is:

1. A self-contained steam heating unit comprising a steam coil having its ends connected to provide a continuous passage 40 through the same, a dead-end connection from the bottom of the coil, heating means for the dead-end connection, and an enclosing casing for the connection and its heating means.

2. A self-contained steam heating unit comprising an endless steam coil, a dead end connection leading outward from the lower turn of the coil, a source of heat for the dead-end connection and a fire box enclosing the connection and the source of heat.

3. A self-contained steam heating unit comprising a steam coil having its ends connected by a chambered member, a dead-end connection from the lower end of the said member, heating means for the dead-end connection and the chambered member, and a fire box enclosing the heating means.

4. A self-contained steam heating unit comprising a steam coil having its ends connected by a chambered member, a dead-end connection from the lower end of the said member, heating means for the dead-end connection and the chambered member, and a fire-box enclosing the connection, the chambered member and the heating means.

5. A self-contained steam heating unit comprising an endless steam coil, air-vents and a water inlet for the coil, the said coil including within its length a chambered member of greater diameter than the coil piping, a connection leading outward from the lowest point of the coil and terminating in a dead-end, means for heating the connection and chambered member, and a non-heat conducting casing for the heating means and parts to which heat is applied.

6. A self-contained steam heating unit comprising an endless steam coil, air-vents and a water inlet for the coil, the said coil including within its length a chambered member of greater diameter than the coil piping, an approximately J-shaped connection leading horizontally outward from the bottom turn of the coil and terminating in a closed end, heating means for the J-shaped connection and chambered member, and a nonheat conducting casing for the connection and its heating means, the said casing being provided with air inlets and an outlet flue for the casing.

7. A self-contained steam heating unit comprising a flat coil, air valves and a water inlet for the coil, the said coil having its ends connected by a vertically disposed chambered member, a dead-end connection from the said member forming a continuation of the coil and extending outward beyond the member, heating means for the dead-end connection and the chambered member, a casing enclosing the heating means and parts heated by said means, and a baffled outlet flue for the casing.

I affix my signature.

DANIEL W. LENAHAN.
